UNITED STATES PATENT OFFICE.

ANNETTA M. WILSON, OF INDIANAPOLIS, INDIANA.

DRYING RACK.

Application filed June 9, 1926. Serial No. 114,816.

My said invention relates to drying racks for clothes. One object of my invention is to construct a rack that can be fastened to the ordinary forms of steam or hot water radiators used in homes, hotels or apartment houses.

Another object is to make the rack collapsible and of light weight so that it may be packed in a suit case or traveling bag for the use of tourists or other persons who may desire to dry light articles such as handkerchiefs, stockings or the like in their rooms.

Another object is in the manner of mounting the rack so that it and its contents are not visible from the outside through the window of the building and the light and ventilation from the window are not obstructed.

20 Referring to the accompanying drawings which are made a part hereof and on which similar reference characters indicate similar parts,

Figure 1 is a perspective of a radiator located next to a window with my improved drying rack installed thereon,

Figure 2, a plan view of one support showing a portion of the radiator in horizontal section,

30 Figure 3, a vertical section on line 3—3 of Figure 2, and

Figure 4, a detail of one of the extension arms.

In the drawings reference character 10 represents the wall of a room provided with a window 11. A radiator 12 of ordinary sectional construction curved together by tie rod 13 is located adjacent the window.

40 My improved rack consists of a duplicate pair of approximately diamond-shaped brackets 14 of light but strong metal each having a rearwardly extending arm 15 and a downwardly extending arm 16. A perforated plate 17 is secured to or formed integral with the lower end of the arm 16 and at right angles thereto and the perforation receives one end of a bolt 18 threaded to receive a wing nut 19 while the headed end of the bolt passes through a rectangular plate 20, all as will be hereinafter more fully described.

Each bracket 14 is perforated as at 21 to receive the clothes lines 22 which are knotted after being passed through the perforations 21 to prevent them from pulling out. The device described constitutes the major por-

tion of my invention and it is secured to the radiator by inserting the arms 15 of each bracket between the end coils of the radiator 12 and beneath the upper rod 13, 60 then the bolt 18 is inserted from the rear with the plate 20 bearing against the rear coils of the radiator. The threaded end is passed through the perforation in the plate 17 and the nut 19 is tightly clamped. The 65 strain of the weight of the garments on the lines will bear on the plate 17 while the arm 15 will prevent the brackets 14 from swinging forward.

As a means for providing additional lines, 70 I provide detachable extensions comprising arms 23 having T-shaped heads 24 on one end adapted to enter a rectangular slot 25 in the brackets 14. The arms 23 are provided with short slots 26 adapted to fit down over a headed lug 27 secured to each bracket 14 thereby preventing any loose motion between the extension and the bracket 14. Perforations 28 are provided in the arms 23 through which additional clothes lines 29 may be 80 passed and secured in the same manner as the lines 23.

A drying rack of this construction affords from 10 to 15 feet of clothes line and can easily be attached to the radiator or when 85 not in use may be collapsed into a flat space for the convenience of packing or storing into a suitcase, trunk, etc.

It will be obvious to those skilled in the art that various changes may be made in 90 my device without departing from the spirit of the invention and therefore I do not limit myself to what is shown in the drawings and described in the specification but only as indicated in the appended claims. 95

Having thus fully described my said invention, what I claim as new and desire to secure by Letters Patent, is:

1. A portable clothes drying rack adapted to be secured to a steam radiator, said rack 100 comprising a pair of brackets perforated to receive drying lines, means for attaching said brackets to extend outwardly in front of said radiator, means for preventing said brackets from sagging, and detachable means 105 for providing more drying lines, substantially as set forth.

2. A portable clothes drying rack of the class described comprising a pair of brackets, perforations in said brackets to receive the 110 ends of the clothes lines and detachable extensions carried by said brackets for sup-

porting additional clothes lines, substantially as set forth.

3. A portable clothes drying rack of the class described comprising a pair of brackets, perforations in said brackets to receive the ends of clothes lines, detachable extensions for supporting additional clothes lines comprising perforated arms with a T-shaped head on the end of said arms and

a rectangular slot in said bracket adapted to 10 receive said T-head, a pin secured to said bracket, and a slot in said arm to receive said pin, substantially as set forth.

In witness whereof, I have hereunto set my hand and seal at Indianapolis, Indiana, this 7th day of June, A. D. nineteen hundred and twenty-six.

ANNETTA M. WILSON. [L. s.]
